PAPER FASTENER

Frederick C. Houwen, Morris Plains, N. J., assignor to The Bates Manufacturing Company, West Orange, N. J., a Corporation of New Jersey

Application February 10, 1933. Serial No. 656,078

10 Claims. (Cl. 24—153)

My invention relates to paper fasteners and more particularly to that type of fastener adapted to clamp or secure together perforated and superimposed sheets of paper such as those that make up ordinary correspondence files.

A common form of such a fastener consists of an elongated base or clamping member having spaced bendable fingers or tongues, and a keeper comprising an elongated plate having spaced openings through which the fingers of the clamping member, after being inserted through perforations in the sheets to be secured together, are designed to be passed and then bent down over the keeper plate. The keeper 10 may, as is customary, also include locking members slidably mounted on said plate and adapted to cooperate with the bent down fingers to hold the same and thereby the clamping member and keeper plate in operative clamping relation with 15 respect to the sheets secured thereby. It is to fasteners of this general construction that my invention is especially directed, but it is to be understood that certain features thereof are applicable to fasteners of many different forms. 20 It is the general purpose of my invention to provide a fastener of the character described which is of improved, simple and practicable construction and also very effective and satisfactory in use.

One of the principal objects of my invention is to provide an improved construction for a fastener keeper plate whereby such plate even though formed of comparatively thin sheet metal, will be very strong, rigid and resistant to deformation, especially at the end portions thereof.

Another object of my invention is to provide an improved, simple and very effective construction for strengthening or reinforcing and increasing the rigidity of the end portions of the keeper plate of a fastener such as described above.

Another object of my invention is to provide such a reinforcing or strengthening construction for the end portions of the keeper plate which presents no sharp or rough surface portions over which the fingers or thumbs of the user must be moved or slid in the operation of bending the fingers of the clamping member and pressing them down over the keeper plate.

A further object of my invention is to provide a substantially rectangular fastener keeper plate having the improved reenforcing features just described and in which the end portions of the plate are unflared but are of substantially the same width as the intermediate portion.

A still further object of my invention is to provide improved stopping means for limiting the outward movement of the locking members on the keeper plate.

Other objects and advantages of my invention will be hereinafter more fully described, and the novel features thereof will be set forth in the claims.

For a clearer understanding of my invention, attention is directed to the drawing accompanying and forming part of this specification, in the several views of which like parts are designated by the same reference characters, and in which:

Figure 1 is a sectional view showing a plurality of superimposed sheets of paper secured together 70 by a fastener constituting a preferred embodiment of my invention, the fastener being shown in elevation partly in section;

Figure 2 is a plan view of the fastener in operative assembled condition, the construction being 75 substantially the same as shown in Figure 1 except for the slide stopping means of the keeper plate;

Figure 3 is a central longitudinal sectional view of the keeper of the fastener shown in Figure 2; and

Figure 4 is a bottom plan view of the keeper shown in Figures 2 and 3.

The fastener shown in the drawing is formed of thin sheet metal and comprises a clamping or base member having an elongated substantially rectangular ribbed base portion 1 and bendable but resilient flat fingers or tongues 2 integrally joined to the base portion at its ends, and a keeper comprising an elongated plate 3 having narrow 85 rectangular openings 4 adjacent its ends through which the fingers 2 are adapted respectively to be passed and then bent inwardly and downwardly over the plate. The keeper plate 3 has a continuous central rectangular depressed portion 5 extending longitudinally thereof between points which are respectively located a slight distance outwardly of the outer edges of the openings 4. The lateral edge portions 6 at the opposite sides of the portion 5 lie in a common plane spaced 90 somewhat above the plane of the latter, and constitute similar parallel spaced rails on which locking members 7 for the fingers 2 are mounted for sliding movement. The depressed portion 5 provides a channel space between the rails 6 of a 100 width slightly greater than that of the fingers 2 and is joined to the rails 6 by vertical walls 8 which act to reinforce the keeper plate. This channel is adapted to receive the free end portions of the fingers when the latter, in applying 110

the fastener to use, are passed through the perforations 9 in the sheets S (see Figure 1) to be secured together and the openings 4 in the keeper plate and are bent inwardly and downwardly against such plate. The locking members 7 have intermediate or bridge portions extending across the channel between rails 6 and adapted to take over the bent down free end portions of the fingers 2 to hold the latter and the keeper plate in operative clamping relation, and end portions 7' which extend over and are bent down under the rails. When the fastener is in operative clamping relation with respect to the stack of superimposed paper sheets S to be secured thereby, as shown in Figure 1, the bottom surface of the depressed portion 5 of the keeper plate bears against the paper and the rails 6 are spaced somewhat above the same. Accordingly the paper will then in no way interfere with the free movement of the locking members 7 along the rails.

The depressed portion 5 of the keeper plate 3 terminates a short distance outwardly of the openings 4 and is joined by nearly vertical but slightly outwardly inclined end walls 10 to the end sections of the plate. Each of the said end sections comprises a flat narrow inner portion 11 which is in the same plane as and joins the rails 6, a narrow outer portion 12 which extends downwardly in an abrupt but smooth incline from the portion 11 to or substantially to the plane of the bottom surface of the depressed portion 5, and substantially vertical portions or flanges 13 at its opposite sides which are substantially flush with the latter outer edges of the rails 6. The surfaces of the flanges 13 at the end sections of the keeper plate are preferably slightly curved where they join the surfaces of the adjacent portions 11 and 12 so as to smoothly merge with or run into the latter surfaces, and the lower edges of said flanges incline upwardly from the corresponding extreme ends of the plate until they respectively meet and merge with the outer edges of the rails 6 at points which, lengthwise of the plate 3, are adjacent the corresponding openings 4. The end sections of the keeper plate thus constructed are very strong and rigid and extremely resistant to forces tending to deform the same, even when the keeper plate is made of quite thin sheet metal. These sections also have smooth surfaces which present no sharp edges or rough portions to cut or obstruct the fingers or thumbs as the latter are slid inwardly thereover from the outer ends of the keeper plate in the operation of bending the end portions of fingers 2 down over the said plate into the channel provided by the depressed portion 5 after the fingers 2 have been passed through the openings 4.

The plate 7 is preferably formed of a single piece of suitable sheet metal and pressed to the form shown and just described. In the operation of pressing the keeper plate to form, the lateral edge portions of the plate corresponding to the depressed portion 5 are drawn inwardly and the plate is thereby provided at the opposite sides of its end sections with portions which if unsubjected to any forming operation would flare to the respective adjacent ends of the plate, but which are formed by pressure into the substantially vertical side flanges 13. The length of the flanges 13 and accordingly the points at which their inner ends terminate in respect to the openings 4, may be regulated, within limits, by making the depressed portion 5 in the keeper plate of proper length with its end walls 10 located 75 a suitable distance outwardly beyond the respec-

tive adjacent openings 4. In the keeper plate shown in Figure 1, the depressed portion 5 is made of such length that the end walls 10 are located only a short distance from the respective openings 4. Accordingly in the case of the plate shown in this figure, the side flanges 13 of the end sections are of such length that they terminate at their inner ends and merge with the side edges of rails 6 at points which are located a short distance inwardly of the respective openings 4. With this construction, the inner ends of the flanges 13 constitute stops for the slidable locking members 7 and prevent such members being moved outwardly on the keeper plate to positions in which they extend over or partly over the respective adjacent openings 4. In the construction shown in Figures 2, 3 and 4, however, the depressed portion 5 is made longer with the end walls 10 at a somewhat greater distance from the outer edges of the respective openings 4. Therefore in this case the inner ends of the flanges 13 terminate a short distance outwardly from the inner edges of the respective adjacent openings 4. The stops for the members 7, when the keeper plate is of the construction last described, may be projections 14 struck from or otherwise provided on the rails 6 at points located a slight distance inwardly from the inner edges of the respective adjacent openings 4.

It is to be understood that the specific constructions shown and described herein are merely illustrative, and that the same are subject to many modifications without departure from the spirit of my invention or the scope of the appended claims:

Having now fully described my invention, I claim:

1. A keeper for a paper fastener comprising a substantially rectangular plate having horizontal lateral edge portions located in the same plane, a longitudinally extending depressed portion disposed between said lateral edge portions and terminating short of the ends of the plate, and end sections each comprising an inner portion joined to the adjacent end wall of the depressed portion and to said lateral edge portions and disposed in the same plane as the latter and an outer portion inclining abruptly downwardly from said inner portion substantially to the plane of said depressed portion.

2. A keeper for a paper fastener comprising an elongated plate of sheet metal having horizontal parallel edge portions, a longitudinally extending depressed portion located between said edge portions and terminating short of the ends of the plate, and end sections each comprising an inner portion disposed substantially at the level of said edge portions and connecting the same, an outer portion smoothly joining said inner portion and abruptly decreasing in height from the latter towards the end of the plate, and substantially vertical portions at its opposite lateral edges.

3. A keeper for a paper fastener comprising a substantially rectangular integral thin metal plate having horizontal lateral edge portions in a common plane, a longitudinal depressed portion disposed between said edge portions and terminating short of the ends of the plate, and end sections each comprising an inner portion connecting and located in the plane of said edge portions, an outer portion inclining abruptly downwardly from said inner portion and vertically extending opposite side portions which are respectively substantially flush with the outer edges of the said horizontal lateral edge portions.

4. A keeper for a paper fastener comprising a substantially rectangular integral thin metal plate having horizontal lateral edge portions in a common plane, a longitudinal depressed portion between said edge portions terminating short of the ends of the plate and provided adjacent its ends with openings for the reception of the fingers of a fastener clamping device, and end sections each comprising an inner portion connecting and located in the plane of said edge portions, an outer portion inclining abruptly downwardly from said inner portion, and vertically extending opposite side portions the lower edges of which respectively incline upwardly from the corresponding end of the plate to meet the said horizontal lateral edge portions at points located adjacent the corresponding opening in said depressed portion. 5. A keeper for a paper fastener comprising a substantially rectangular integral thin metal plate having horizontal lateral edge portions in a common plane, an intermediate longitudinal depressed portion terminating short of the ends of the plate and provided adjacent its ends with openings for the reception of the fingers of a fastener clamping device, and end sections having spaced substantially vertical reinforcing portions extending lengthwise of the plate, and locking members slidably mounted on said lateral edge portions, the said reinforcing portions of the opposite end sections of the plate constituting stops for limiting outward movement of said locking members. 6. A keeper for a paper fastener comprising a substantially rectangular integral thin metal plate having horizontal lateral edge portions in a common plane, a longitudinal depressed portion between said edge portions terminating short of the ends of the plate and provided adjacent its ends with openings for the reception of the fingers of a fastener clamping device, and end sections each comprising an inner portion connecting and located in the plane of said edge portions, an outer portion inclining abruptly downwardly from said inner portion, and vertically extending opposite side portions the lower edges of which respectively incline upwardly from the corresponding end of the plate to meet the said horizontal lateral edge portions at points located adjacent but inwardly of the corresponding opening in said depressed portion. 7. A keeper for a paper fastener comprising a substantially rectangular integral thin metal plate having horizontal lateral edge portions in a common plane, an intermediate longitudinal depressed portion terminating short of the ends of the plate and provided adjacent its ends with openings for the reception of the fingers of a fastener clamping device, and end sections having spaced substantially vertical reinforcing portions extending lengthwise of the plate, and locking members slidably mounted on said lateral edge portions, the said reinforcing portions of the opposite end sections of the plate constituting stops for limiting outward movement of said locking members. 8. A keeper for a paper fastener comprising a substantially rectangular integral thin metal plate having horizontal lateral edge portions in a common plane, an intermediate longitudinal depressed portion terminating short of the ends of the plate and provided adjacent its ends with openings for the reception of the fingers of a fastener clamping device, and end sections having spaced substantially vertical reinforcing portions extending lengthwise of the plate, and locking members slidably mounted on said lateral edge portions, the said reinforcing portions of the opposite end sections of the plate respectively terminating at their inner ends inwardly of the openings in said depressed portion and constituting stops for limiting outward movement of said locking member. 9. A keeper for a paper fastener comprising a substantially rectangular integral thin metal plate having horizontal lateral edge portions in a common plane, an intermediate longitudinal depressed portion terminating short of the ends of the plate and provided adjacent its ends with openings for the reception of the fingers of a fastener clamping device, and end sections having spaced substantially vertical reinforcing portions extending lengthwise of the plate, locking members slidably mounted on said lateral edge portions, the said reinforcing portions of the opposite end sections of the plate terminating short of the inner edges of the respective openings in said depressed portion, and stops for said locking members provided on said horizontal lateral edge portions adjacent but inwardly of the said openings. 10. A keeper for a paper fastener comprising a substantially rectangular integral thin metal plate having horizontal lateral edge portions in a common plane, an intermediate longitudinal depressed portion terminating short of the ends of the plate and provided adjacent its ends with openings for the reception of the fingers of a fastener clamping device, and end sections having spaced substantially vertical reinforcing portions extending lengthwise of the plate and locking members slidably mounted on said lateral edge portions, the said reinforcing portions of the opposite end sections of the plate terminating short of the inner edges of the respective openings in said depressed portion, said horizontal lateral edge portions having projections located adjacent but inwardly of said openings and constituting stops for limiting the outward movement of said locking members.

FREDERICK C. HOUWEN.
